UNITED STATES PATENT OFFICE.

PAUL A. MEEHAN, OF NEW CASTLE, PENNSYLVANIA, ASSIGNOR TO AMERICAN DRESSLER TUNNEL KILNS, INC., OF NEW YORK, N. Y., A CORPORATION OF NEW YORK.

CAR FOR TUNNEL-KILNS.

1,328,749.

Specification of Letters Patent.

Patented Jan. 20, 1920.

Application filed April 8, 1919. Serial No. 288,651.

To all whom it may concern:

Be it known that I, PAUL A. MEEHAN, a citizen of the United States, and resident of New Castle, in the county of Lawrence and State of Pennsylvania, have invented 5 certain new and useful Improvements in Cars for Tunnel-Kilns, of which the following is a specification.

My present invention consists in improvements in the construction of cars especially 10 devised for use as goods carrying cars for tunnel kilns, and the general object of my invention is to provide a simple and relatively inexpensive car construction well 15 adapted to stand the severe operating conditions incident to its use in highly heated kilns having wheel mountings such that wheels may be readily taken out and replaced when necessary for inspection, repair 20 or renewal.

The various features of novelty which characterize my invention are pointed out with particularity in the claims annexed to and forming a part of this specification. 25 For a better understanding of the invention, however, and the advantages possessed by it reference should be had to the accompanying drawings and descriptive matter in which I have illustrated and described a 30 preferred embodiment of my invention.

Of the drawings—

Figure 1 is a transverse section of a tunnel kiln, and one of my improved cars therein.

Fig. 2 is a side elevation of the car frame and rails.

Fig. 3 is a partial section on the line 3—3 of Fig. 2.

Fig. 4 is a plan view of the car portion shown in Fig. 2.

In Fig. 1, I have illustrated the use of my invention in a tunnel kiln of the Dressler type, but it is to be understood that my improved car construction is not necessarily 45 restricted to use in this particular type of tunnel kiln. In the tunnel kiln shown, A represents the masonry of the kiln inclosing the kiln chamber A¹ proper and a lower chamber A² normally filled by the bodies of the 50 train of cars D moving through the kiln along the track rails C. In the kiln chamber A¹, proper, combustion chambers B are provided at the opposite sides of the pathway for the goods K mounted on the cars D. Air circulating channels B¹ are formed

about the combustion chambers B and the refractory goods supporting bodies E of the cars D are provided with tunnels E¹ to permit a circulation of the heated atmosphere in the tunnel chamber A¹ upward 60 past the combustion chambers and downward through or along the goods, K. In so far as it is specifically described above, the construction illustrated contains nothing now novel with me.

Each car comprises a metallic car frame advantageously in the form of a single steel casting on which the refractory body E formed of fire brick or the like is mounted. Each car also comprises a plurality of supporting wheels G and G¹ and the present invention relates primarily to the manner in which these wheels are mounted in the car frame. As shown each car has four wheels one at each corner of the car. These four 75 wheels are all alike except that, as shown, the two wheels G at one side of the car are provided with double flanges while the wheels G¹ at the other side of the car are unflanged. Each wheel is journaled on a 80 separate supporting axle F, advantageously a roller bearing comprising rolls H and guide rings H¹ being interposed between each axle and the bore of the corresponding wheel G or G¹. The body of each axle F 85 is cylindrical, but the ends of the axle are reduced to provide flat sides F¹, and preferably also as shown the ends of the axles have flat upper edges F². The reduced and flattened axle ends fit in recesses or seats D² 90 formed in flanges D¹ which are arranged to form guides or shrouds at the opposite sides of each wheel. Each of the seats D² is open at its lower end so that each wheel may be removed from the car frame for inspection, 95 repairs or renewal of the wheel, axles or bearings by simply jacking up the car frame, or by lowering the car wheel while holding the car frame stationary. To prevent accidental dislocation of the axles F 100 resulting from track inequalities or the like, a bolt I may be mounted in the flanges D¹ beneath each end of each axle F. These bolts are preferably secured in place by cotter pins J as shown. To permit of lubrication of the wheel bearings when this is desired, a hole F³ is drilled in the outer end of each axle. Lubricating material may be squirted or otherwise put into the bearings 105 through these holes.

110

To strengthen the metallic car frame and to restrict the flow of hot air or other gaseous medium in the tunnel downward about the wheels and track rails to thereby raise 5 the temperature to which the lower portion of the car is subjected, the metallic car frame is formed at its under side with transverse flanges or webs D³, D⁴ and D⁵. The upper side of the metallic car frame is also 10 formed with ridges or flanges D⁶ for strengthening the metallic car frame portion of the car and for anchoring the refractory body material in place.

The wheel mounting described is characterized by its obvious simplicity and ruggedness and by the provisions made for protecting the wheel mountings from the high temperatures to which the goods K may be subjected. This temperature is frequently 20 as high as, and is sometimes higher than 2500° Fahr. Notwithstanding the simplicity of the construction, each wheel is securely held in place in operation while it may readily be removed from the car frame 25 when necessary. Such warping of parts as may normally be expected in practice under the temperature conditions to which the car is subjected are not apt to materially interfere with the practical effectiveness of the 30 car wheel mountings.

While in accordance with the provisions of the statutes I have illustrated and described the best form of my invention now known to me it will be apparent to those 35 skilled in the art that changes may be made in the form of the apparatus disclosed without departing from the spirit of my invention as set forth in the appended claims and that certain features of my invention may 40 sometimes be used without a corresponding use of other features.

Having now described my invention, what I claim as new and desire to secure by Letters Patent, is:

45 1. A car of the type specified, comprising

in combination a plurality of supporting wheels, a separate axle for each of said wheels and a metallic car frame mounted on said wheels and formed with depending flanges arranged one at each side of each 50 wheel and recessed to provide bearing seats open at their lower ends for and positively engaged by each of said axles.

2. A car of the type specified, comprising in combination a plurality of supporting 55 wheels, a separate axle for each of said wheels and a metallic car frame mounted on said wheels and formed with depending flanges arranged one at each side of each wheel and recessed to provide bearing seats 60 open at their lower ends for and positively engaged by each end of each of said axles, said recesses and the ends of said axles being so relatively shaped as to prevent rotation of each axle in its seat. 65

3. A car of the type specified, comprising in combination a plurality of supporting wheels, a separate axle for each of said wheels having reduced and flattened ends, a metallic car frame mounted on said wheels 70 and formed with depending flanges arranged one at each side of each wheel and recessed to provide bearing seats open at their lower ends for and positively engaged by each end of each of said axles, said recesses and the reduced ends of said axles 75 being so relatively shaped as to prevent rotation or endwise movement of each axle in its seat, and roller bearings interposed between the axles and the wheels journaled thereon, and held against endwise displacement by said flanges. 80

Signed at the city of New Castle, in the county of Lawrence and State of Pennsylvania this fifth day of April, A. D. 1919.

PAUL A. MEEHAN.

Witnesses.

JAMES A. CHAMBERS,
JOHN P. LOCKHART.
